US00D496655S1

(12) **United States Design Patent** (10) Patent No.: **US D496,655 S**
Harries et al. (45) Date of Patent: **** Sep. 28, 2004**

(54) **KEYBOARD OF AN ELECTRONIC COMMUNICATION DEVICE**

(75) Inventors: **Andrew Harries**, Vancouver (CA); **Jon Theron Winebrenner**, Vancouver (CA); **Jamian Russell Cobbett**, Portland, OR (US); **Mark H. Hoeveler**, Portland, OR (US); **Stephen Matthew McCallion**, Portland, OR (US); **Norman Roy Eldridge**, Richmond (CA)

(73) Assignee: **Sierra Wireless, Inc.** (CA)

(**) Term: **14 Years**

(21) Appl. No.: **29/196,579**

(22) Filed: **Dec. 31, 2003**

Related U.S. Application Data

(63) Continuation of application No. 29/173,586, filed on Dec. 30, 2002, now abandoned.

(51) LOC (7) Cl. **14-03**

(52) U.S. Cl. **D14/247**

(58) Field of Search **D14/137, 138, D14/218, 147-148, 247-248, 144, 341-347; 379/433.01-433.13, 419, 434, 428.01-428.04, 420.01-420.04, 440; 455/550.1-90.3; D21/517; D13/168; D18/2, 7; 345/168, 169**

(57) **CLAIM**

The ornamental design for a keyboard of an electronic communication device, as shown and described.

DESCRIPTION

FIG. 1 is an isometric view of a first embodiment of a keyboard of an electronic communication device in accordance with the present invention.

FIG. 2 is a front elevation view of the keyboard of FIG. 1. FIG. 3 is an isometric view of a second embodiment of a keyboard of an electronic communication device in accordance with the present invention; and,

FIG. 4 is a front elevation view of the keyboard of FIG. 3. The broken lines showing throughout all views of both embodiments are for illustrative purposes only and form no part of the claimed design.
